ADJUSTABLE FASTENER FOR WREATH
FRAMES AND EASELS

Robert C. Aughtry, Haskell, Tex.

Application July 26, 1934, Serial No. 737,092

2 Claims. (Cl. 248—34)

This invention relates to methods and devices for fastening floral wreaths and wreath frames to any conventional form of supporting easel. Floral wreaths as commonly made up at the present time consist of an open wire framework packed with some special form of moss as a filler, and upon which frame as a base the flowers are mounted for completing the wreath. The wreath frame is then secured to the easel by means of pieces of wire which are extended around the wires of the frame and the legs of the easel and then twisted together at their ends. This method of mounting the frames upon the easels is necessarily tedious and more or less unsatisfactory, as will be readily apparent.

The primary object of the present invention therefore is to provide a simple, practicable and adjustable form of fastener for releasably securing such wreath frames to their easels, and which 20 may be adapted for use upon various styles and makes of wooden or iron easels, having either round or square legs, or upon easels constructed of heavy wire. Another object is to provide various forms of adjustable hooks or fasteners, all 25 operating upon the principle of slidably and frictionally engaging the legs of the easels, for mounting upon easels of various kinds, the said fasteners being thus rendered efficient for quickly and firmly securing the wreath frames to the 30 said easels.

With the foregoing objects and advantages in view, together with such additional advantages as may appear from the following specification, attention is now directed to the accompanying 35 drawings as setting forth certain preferred embodiments of my invention, the said drawings constituting a part of the specification, and wherein:

Figure 1 is a frontal elevation of a wreath frame as secured upon a conventional form of easel 40 thru the employment of a form of fastener constructed in accordance with this invention.

Figure 2 is a side elevation of the assembly of Figure 1.

Figure 3 is an enlarged detail of the form of fastener employed in Figures 1 and 2, the same being shown as mounted upon a fragment of a round, iron or wire easel leg, the same representing the form of the fastener well adapted for use at the lower side of the wreath frame.

Figure 4 is a view similar to that of Figure 3, the same representing the form of fastener adapted for use at the upper side of the wreath frame, complementarily to the lower fastener of Figure 3.

Figure 5 is a view similar to that of Figure 3,

the fastener being shown as formed for mounting upon a squared wooden leg of an easel.

Figure 6 is a frontal elevation of an easel having legs longitudinally slotted, and having a wreath frame mounted thereupon by means of a modified form of fastener adapted to co-operate with said slots, the wreath frame being represented in dotted lines.

Figure 7 is an enlarged section on the line 7—7 of Figure 6.

Figure 8 is an enlarged detail in side elevation of the same modification of the fastener represented in Figures 6 and 7.

Figure 9 is an enlarged side elevation of still another modified form of fastener as mounted 15 upon a round wooden leg of an easel, a fragment of the latter being shown.

Figure 10 is a top plan view of the assembly of Figure 9, the easel leg being shown in section.

Two conventional forms of floral easels are 20 represented in Figures 1, 2 and 6, and therein referred to generally at A and B. Each includes two frontal legs A1 and B1 pivotally connected at their upper ends to the rear legs A2 and B2, these connections being made in any conventional manner, such as indicated at A3 and B3. The legs of such easels are commonly made of heavy wire, as represented at A1—A2 in the Figures 1 to 4, in which case they are of course round in cross section, or they may be made of wood 25 and round in cross section, as represented at B1—B2 in Figures 6 to 8, or they may be of wood and square in cross section, as represented at C1 in Figure 5.

The present invention comprises various forms 35 of adjustable fasteners 10a—11a of Figures 1 to 4, 10b—11b of Figures 6 to 8, 11c of Figure 5, and 11d of Figures 9 and 10, all formed with loops, rings or spanner portions designed to slidably and frictionally engage the legs of the easels, 40 whatever may be the form of those legs.

In the forms shown in Figures 1 to 4 the fasteners are made of wire and include the ring or spanner portions 12a and the hook portions 13a, the spanner portions or rings being adapted to 45 loosely encircle the frontal legs A1 of the easel A. In the use of this form of fastener, two pairs of fasteners are mounted upon the frontal legs of the easel, one pair 10a being disposed upwardly upon the legs and with the hooks turned upwardly, and the other pair 11a being disposed downwardly upon the same legs and with the hooks turned downwardly, all as clearly shown in Figures 1 and 2. The wreath frame E is then suspended from the upper pair of hooks by merely 50 55

engaging certain wires of the frame therewith, as represented at 14a, after which the lower hooks are likewise brought into engagement with the frame, as represented at 15a. The lower hooks 5 11a are then pressed downwardly, slidably over the legs of the easel for the purpose of tensioning the frame and firmly supporting same between the upper and lower sets of hooks. In this operation the looseness of the encircling 10 rings upon the easel legs readily allow them to slip over the legs when the planes of the rings are positioned perpendicularly to the axes of the legs; however, when the adjustment is completed and the rings released, they frictionally pinch 15 and bind upon the legs, and any reverse movement or slippage of the fasteners is prevented thru this pinching action of the rings upon the legs under the strain imposed thru the original tensioning of the wreath frame.

20 In order to facilitate downward pressure upon the lower fasteners 11a, handles 16a may be extended rearwardly therefrom, and as these handles are pressed down, the hooks 13a being engaged by the wreath frame, it is obvious that the 25 rings to which the handles are attached, will be forced down angularly on the easel legs with the portions next to the handles most depressed, and thus positioned to instantly frictionally lock 30 themselves upon the legs when pressure is removed from the said handles.

The modified form of fasteners 10b—11b shown in Figures 6 to 8, are designed for use upon a form of easel B having legs B1 which are provided with the upper and lower pairs of longitudinally extended slots B4. In lieu of the ring portions 12a of the previous form, the fasteners here shown are formed with spaced stops 12b adapted to pass freely thru the slots of the legs when turned into registry therewith for that purpose. When this is done the stops are turned perpendicularly to the slots, thus spanning the legs at either side thereof, where they function for frictionally gripping the legs of the easel in a manner exactly similar to the rings of the form 45 previously described. Thus this form of the fasteners may be readily mounted upon the legs B1 thru the slots B4.

In the remaining modified form of the fasteners 11d as shown in Figures 9 and 10, the 50 spanner portions of the fasteners are formed into loops 12d, open at one side as shown, and thru which side the leg D1 of the easel may be inserted in locating these fasteners upon the easel. The operation and function of this form of the fastener are the same as for the other forms shown.

The structures shown in Figure 5 conform substantially to those of the other views and already described, the only difference being that the spanner element 12c is formed square for

engaging the squared leg C1 of the easel here represented.

It will be understood that in positioning the upper pair of fasteners upon the easel legs, the weight of the wreath frame imposed upon them 5 will operate to tilt the hooks downwardly and so result in the spanner portions pinching the legs and frictionally maintaining themselves in place while the lower fasteners are being adjusted in manner already pointed out. It will therefore 10 be obvious that the gripping action of both the upper and lower sets of the fasteners is due to the tilt or angularity imparted to them thru the weight and strain of the wreath frame upon the hooks of the fasteners. Thus it will be seen that 15 I have here shown and described a very simple and effective means for quickly and securely mounting wreath frames upon easels of various kinds, and it is obvious that the frames may be as easily adjusted or removed whenever desired; 20 and while I have herein shown and described certain preferred embodiments of my invention, together with certain structural features well adapted to carry out the purposes thereof, it is understood that I am not to be limited to the 25 several features or structures shown, but that I may vary same as may be found expedient in practice, not departing however from the spirit of the invention as defined in the appended claims.

I claim:

1. In a device of the kind described for fastening a wreath frame upon an easel having a supporting leg, the combination of a spanner element in the form of an open loop adapted to engage the leg of the easel thru its open side, means on the spanner for engaging a wreath frame, and a handle extended oppositely to the said wreath frame engaging means.

2. A pair of fasteners for securing a wreath 40 frame upon an easel having legs, the fasteners including spanner portions having inside diameters greater than the diameters of the legs and thus adapted for loosely and slidably engaging the legs of the easel when turned right angularly thereto and for frictionally locking upon those legs when tilted out of said right angular relation to the legs, whereby the fasteners when engaging opposite portions of the wreath frame and correspondingly spaced portions of the legs 50 of the easel, may be drawn taut against the contrary strain of the wreath frame and may be tensioned against each other to tilt them out of their right angular relation to the legs of the easel, for frictionally locking them to the legs 55 in any desired adjusted position, said fasteners having handles extended therefrom for facilitating the tilting and adjustment of same.

ROBERT C. AUGHTRY.
